UNITED STATES PATENT OFFICE

111,347

DESIGN FOR A FURNACE LIGHTER

Alfred Porkolab and Benjamin M. Vecchio,
Lorain, Ohio

Application June 14, 1938, Serial No. 77,839

Term of patent 3½ years

To all whom it may concern:

Be it known that we, Alfred Porkolab and Benjamin M. Vecchio, citizens of the United States, residing at Lorain, in the county of Lorain and State of Ohio, have invented a new, original, and ornamental Design for a Furnace Lighter, of which the following is a specification, reference being had to the accompanying drawing, forming part thereof.

Figure 1 is a view in front elevation of a furnace lighter, showing our new design.

Figure 2 is a view in side elevation thereof.

Figure 3 is a top plan view.

We claim:

The ornamental design for a furnace lighter, as shown.

ALFRED PORKOLAB.
BEN. M. VECCHIO.
